Application September 28, 1945, Serial No. 619,222

3 Claims. (Cl. 178—22)

1

This invention relates to code and cipher systems, and more in particular to systems wherein language messages are translated automatically to and from a coded or ciphered form.

For some purposes, the terms "code" and "cipher" have been used interchangeably, but this has led to some confusion. For convenience, the term "code" is here used to designate a system such as the Baudot code, where each of the letters of the alphabet is represented by a specific signal with the same signal being used for any specific letter each time that that letter appears; and, the term "cipher" is here used to designate a system of secret communication where there is a substitution of characters or other effect whereby, for example, a specific letter of the alphabet is not represented by the same signal each time that that letter appears. In the illustrative embodiments of the invention, a coded message may be translated into an irregular chain cipher which is a cipher system where the ciphering effect is changed constantly during the ciphering of a message. Normally the cipher key is incoherent and, for all practical purposes, the cipher herein explained is an endless chain cipher wherein the cipher key need not be repeated during the length of the normal message.

An object of this invention is to provide a simple and versatile code and cipher system which will code and decode as well as encipher and decipher language messages in a rapid and dependable manner. A further object is to provide for the systematic or monsystematic coding of messages with simple apparatus. A still further object is to provide apparatus for carrying out the above which is compact and sturdy in construction, inexpensive to manufacture and maintain, and which is adaptable to many uses without material changes in construction. A still further object is to provide apparatus of the above nature wherein the cipher system can be easily changed or annulled. These and other objects will be in part obvious and in part pointed out below.

The invention accordingly consists in the features of construction, combinations of elements, arrangements of parts and in the several steps and relation and order of each of the same to one or more of the others, all as will be illustratively described herein, and the scope of the ap-

2

plication of which will be indicated in the following claims.

In the drawings:

Figure 1 is a partially schematic showing of a system representing one embodiment of the invention;

Figure 2 is a partially schematic wiring diagram representing the coding and ciphering arrangement of the embodiment of Figure 1;

Figure 3 is a plan view of the ciphering arrangement of Figure 1 with certain parts broken away;

Figure 4 is a horizontal section showing mechanism for changing the cipher key manually;

Figure 5 is a sectional view on the line 5—5 of Figure 3;

Figure 6 is a sectional view on the line 6—6 of Figure 5;

Figure 7 is a perspective view of a single cipher disc; and

Figure 8 is a partially schematic view representing one manner of changing the cipher key automatically.

In the illustrative embodiment of the invention represented in Figure 1, a typewriting, signal-transmitting and signal-receiving station is represented. This station includes: two electric typewriters 1 and 2 which are each shown as being a commercially known form of electrically

operated typewriter and which are designated "Typwr. No. 1" and "Typwr. No. 2," respectively; two translators 3 and 4 designated "Translator No. 1" and "Translator No. 2," respectively, and associated with the respective typewriters; a tape reader 5 which is of the type disclosed in my co-pending application Serial No. 552,991, filed September 7, 1944, entitled "Tape reader," and which is for the purpose of producing electric signals in accordance with a coded message

punched in a tape; two tape punches 6 and 7, designated "Tape punch No. 1" and "Tape punch No. 2," respectively, and each of the type disclosed in my co-pending application Serial No. 561,179, filed October 31, 1944, entitled "Tape punch," Patent No. 2,432,787, dated December 16, 1947, each tape punch being for the purpose of punching coded or ciphered messages in tape in accordance with electric signals received from the typewriter or from another source; a ciphering unit 8 of the type shown in Figures 3 to 7,

inclusive, and designated "Ciphering unit"; and, electrical wires and switches connecting the various units of the system and here represented schematically by lines and arrows.

Typewriters 1 and 2 and translators 3 and 4 are interconnected so as to form a system of the type disclosed in United States Patent No. 2,307,153, and reference may be had to that patent for a detailed disclosure of this portion of the present system and for the details of construction of the typewriters and translators. It should be noted that each of the typewriters includes a permutation unit, and the pressing of one of the typewriter keys causes the corresponding character to be typed by the typewriter and also causes the permutation unit to produce a set of signal impulses representing the character of the key pressed. These signal impulses are in accordance with the Baudot code, and constitute the coded message which is transmitted over multi-conductor cables to other elements of the system in a manner discussed more fully below.

Each of the translator units is adapted to receive signal impulses representing such a coded message and to translate each set of signal impulses into a designation of a particular key on the typewriter associated with that translator. That is, the set of signal impulses representing a character in accordance with the Baudot code is received by the translator, and these impulses are translated by a series of individually movable cascade-arranged switch elements, whereby one chain or cascade only of the switch elements is closed. The closing of the chain or cascade of switches completes a circuit to the proper key solenoid of the typewriter so as to cause the typewriter to type the character represented by the set of signal impulses.

In accordance with the present invention, the message is translated into a coded message, for example, in accordance with the Baudot code, and then enciphering is produced by superimposing the effect of cipher-signal impulses upon those of the coded message. In this way some or all of the sets of code signal impulses are changed to other permutations so that, in terms of the Baudot code, they represent characters other than the characters which they originally represented. Thus, the original language message is translated into signals of the Baudot code in accordance with the usual code system, and thereafter the coded message resulting from the code signals is altered so as to produce, in effect, a further substitution of one Baudot code element for another. However, this second substitution is not produced in the usual way, but is produced in accordance with an additive and subtractive system, whereby certain of the code elements are changed by one or the other of alternative transformations, whereas others are not.

Illustratively, the system is operated in accordance with a five-unit Baudot code wherein the various letters of the alphabet are represented by a five-place binary code of signals. Each of the typewriters 1 and 2 is capable of typing a language message with the keys being actuated individually by hand or by key solenoids. The key solenoids may be energized from a translator, such as 3 and 4, which receives the coded message and completes the proper circuits to energize the respective key solenoids on the typewriter. Furthermore, when the typewriter is

operated, it may produce the message in coded form through the permutation unit in its base. Tape reader 5 is adapted to receive a tape which is punched with a coded message, and in turn the tape reader produces the message in the coded form, and this message from the tape reader may be transmitted to one of the translators 3 or 4 or it may be transmitted elsewhere.

Each of the tape punches is adapted to receive the coded message, for example, from one of the typewriters or from the tape reader, and the tape punch produces a punched tape having holes therein corresponding to the coded message; this punched tape being of the same type as that which is used to operate the tape reader 5. The ciphering unit 8 also operates in accordance with a five-unit Baudot binary code and it is adapted to receive the signal-impulse coded messages from either of the typewriters or from the tape reader; or it may receive a message from a remote station. The ciphering unit in turn enciphers or scrambles the message in accordance with a predetermined sequential transformation or cipher key, producing a new series of signal-impulse signals based upon the signal-impulse coded message which it receives. The enciphered signal-impulse message may be utilized at the same or a remote station by a tape punch so as to produce a punched tape of the message in cipher, or by a translator and its typewriter to type the message in cipher.

When messages are transmitted in ciphered form, it is desirable that the characters be divided into equal groups regardless of the number of characters in the words of the message. Illustratively, the characters are divided into "code" groups of five characters per group with the groups separated automatically by spaces, which is the preferred form for so-called "coded" telegraphic messages. The basic coding and enciphering systems include the designation of all of the letters of the alphabet, and the spacings between the words of the message, and the auxiliary functions, by code characters; and when the message is enciphered, all of these code characters are enciphered. However, during the coding and enciphering operation, the characters are counted automatically and the telegraphic code character for a space is inserted after each fifth character. The enciphered message then comprises code groups of five enciphered characters each separated by an unciphered telegraphic space character. Thus, if more or less than five characters appear in a group, it is apparent that a fault has occurred either by the omission of a character or characters or by the insertion of extra characters. In this way the remainder of the enciphered or coded message can be translated, and the group where the fault appears can be deciphered or translated separately.

The dividing of the coded or enciphered message into five-character groups also aids when the message is to be read manually, as for example, in transmitting it over a telegraph line. It has been found as a practical matter that an operator can transmit or receive characters in groups of five even though the characters are incoherent. Furthermore, the hiding of the word-division aids in preventing deciphering by unauthorized persons, and yet the division of the characters into groups gives the benefits of a broken chain of characters. Under some circumstances it is desirable to omit the grouping

of the characters and yet to continue the coding or ciphering operations in the usual manner. With the illustrative coding and ciphering system, it is possible to produce a coded or enciphered message having the characters in groups or in an unbroken chain, depending upon which is desired.

In Figure 1 the heavy lines having arrows thereon indicate a particular operating condition for the system which is used to explain the operation; the light lines with arrows thereon represent alternative operating arrangements, all as outlined below. It is assumed that tape reader 5 is reading a tape 9 having a straight language message punched therein in accordance with the Baudot code. For purposes of better understanding, a portion of the tape is shown enlarged and with the language message typed along the edge of the tape. Tape reader 5 transmits the signal-impulse code message to translator 3 over a five-channel electric circuit represented by line 10, and translator 3 closes the circuits of the proper key solenoids through wires represented by line 11 to cause typewriter 1 to type the language message which is being read by the tape reader. This message is typed on a sheet 12, a section of the sheet with the message thereon being enlarged in the insert at the right of the typewriter. The electric-impulse code message from tape reader 5 is also supplied to tape punch 6 through five-channel circuits represented by line 13, and the tape punch reproduces the punched message on a tape 14 a portion of which is shown enlarged in the insert below the tape punch; thus, tape 14 is a reproduction of the original tape 9. Simultaneously the signal-impulse code message from tape reader 5 is transmitted to ciphering unit 8 through a five-channel circuit represented by line 15.

As explained more fully below, ciphering unit 8 enciphers the coded message superimposing onto the original signal-impulse code message a ciphering effect which is the signal-impulse code equivalent of a predetermined incoherent language message, and the resulting signal-impulse enciphered message is transmitted through a five-channel line 16 to tape punch 7. The signal-impulse enciphered message is also transmitted through a five-channel line 165 to translator 4 which controls typewriter 2 through wires indicated by line 166 so that the typewriter types the enciphered message.

The operation of the ciphering unit will now be explained using the five-unit Baudot code with thirty-two character symbols to represent the twenty-six letters of the English alphabet and six added symbols, as for example, numerals 2 to 7 inclusive, which represent non-alphabetic symbols or functions such as Space, Carriage Return, Letters, Figures, etc. Thus, each of the thirty-two language characters is represented by a combination of five signal elements of two characteristics, that is, "on" and "off" or "plus" and "minus" current impulses. The following "Table No. 1" represents these thirty-two characters with the five signal elements for each character symbol represented opposite the respective language characters, the asterisk (*) representing "on" or "plus" and the dash (-) representing "off" or "minus"; and for reasons to be explained more fully below, "Table No. 2" represents these same character symbols in the same order except that the sign of each signal element in the left-hand row (row "#1") has been changed so that

each "on" (*) in this row is now "off" (-) and each "off" (-) is now "on" (*):

As indicated above, Table No. 2 shows the scrambled or mixed alphabet which results from changing the sign of each signal element in row #1. By this simple procedure, each of the code symbols is affected and a completely new derived or mixed alphabet is obtained. By changing the signs of the elements in the various rows, it is possible to obtain thirty-two different mixed alphabets. Thus, any one language character may be represented indiscriminately by any other language character, and if the derived mixed alphabet is changed after each signal impulse, there is no determinable relationship between the sequence of characters in the enciphered message and the sequence of characters in the original message. The application of periodicity and probability tables, slide rules, and other devices employed in the cryptanalysis, is thereby defeated. In practice, the sign of one or more of the five signal elements is changed after each character has been enciphered, and the resulting substitution is in accordance with a predetermined but incoherent cipher key; this results in an endless-chain incoherent cipher or a systematic irregular-chain cipher.

In accordance with the illustrative embodiment of the present invention, the code signals of the message to be enciphered are transmitted to a switching device, and if no cipher effect is desired, each code signal remains unchanged and performs its usual functions to indicate its original language character. However, if it is desired that the message be enciphered, a cipher signal is imposed upon each code signal of the message whereby each symbol is changed by reversing the sign of one or more of the signal elements. A message which has been enciphered may be deciphered by imposing the same cipher signals in the same order for a second time upon the respective signals of the message; that is, the deciphering is brought about by again reversing the signs of the same signal elements

which were reversed during the enciphering of the message. Thus, identical apparatus operating in accordance with the same cipher sequence or key is used for both enciphering and deciphering.

In Figure 2 a circuit arrangement is illustrated whereby a language message which is produced in code by a permutation unit is enciphered automatically by the ciphering unit 8. This enciphered message may be used in the same manner in which any signal-impulse message is used; that is, the enciphered message may be transmitted over suitable channels to a distant station, or it may be used at the same station to operate an electric typewriter, a tape punch or other devices. Referring particularly to the lower left-hand portion of Figure 2, the switch assembly of a permutation unit (of typewriter 1 or 2 of Figure 1) is operated by an electric typewriter (not shown), and the switch assembly includes five permutation switches 17 to 21, inclusive, and two additional switches 22 and 23. The permutation switches are closed by the electric typewriter in various combinations to produce the respective code signals for the various language characters written by the typewriter, illustratively, in accordance with the Baudot code. Switch 22 represents an uncoded function, such as the carriage return and has a key-solenoid assembly 24.

Switch 23 has a normally closed switch unit which is in the circuit of a latch-retaining solenoid 25 which is normally energized by a battery 26. Switch 23 is opened momentarily during each revolution of the permutation shaft, with the result that solenoid 25 is deenergized, and this releases a latch 27 so that a spring 28 swings the latch downwardly and releases a cam 29. When cam 29 is released, it turns one revolution during which time it momentarily closes an impulse switch 30 so as to complete a circuit from battery 26 through switch 30 and thence through such of the permutation switches 17 to 22 as are then closed.

The ciphering unit 8 is represented schematically above and to the right of the permutation unit and includes at the top a set of differential relays 31 to 35 and a set of two-position switches 36 to 40, and at the right a set of switches 41 to 45. Differential relays 31 to 35 have two-position switches 46 to 50, respectively, and differentially wound coil assemblies 51 to 55, respectively. Each of the two-position switches 46 to 50 has a normally closed upper switch-unit designated by the suffix "-2" and a normally open lower switch-unit designated by the suffix "-1". Each of the coil assemblies 51 to 55 comprises a pair of identical differentially-opposed coils which are designated respectively by the suffixes "-1" and "-2"; each pair of coils is connected at a common tap to ground, and either or both of the coils may be energized by connecting the appropriate ungrounded coil end or ends to battery 26. When one only of the coils of any particular coil assembly is energized, the armature of the associated switch is attracted with the result that the armature is moved down so that the upper switch unit is opened and the lower switch unit is closed. However, when both coils of any particular coil assembly are energized, the two coils neutralize each other with the result that the switch armature is not attracted and the associated switch units remain in their normal conditions. Thus, the energization of any one coil causes a reversal of the switch armature; that is, for example, if

the lower coil 51-2 of coil assembly 51 is energized, switch-unit 46-2, will be opened and switch-unit 46-2 closed and switch-unit 46-1 coils 51-1 and 51-2 are energized, the switch armature will remain in its normal position with switch-unit 46-2 closed and switch-unit 46-1 opened. On the other hand, if coil 51-2 is not energized, the energization of coil 51-1 opens switch-unit 46-2 and closes switch-unit 46-1. It is, thus, seen that the energization or deenergization of any one coil in any of the coil assemblies will cause a reversal of the position of the associated switch armature.

The two-position switches 36 to 40 are similar to switches 46 to 50 and have normally open lower switch-units designated with the suffix "-1" and normally closed upper switch-units designated by the suffix "-2." The normally closed switch-units 46-2 to 50-2 are connected in series with the normally open switch-units 36-1 to 40-1, respectively, and the normally open switch-units 46-1 to 50-1 are connected in series with the normally closed switch-units 36-2 to 40-2, respectively. Thus, switch pairs are formed by switches 36 and 46 and 37 and 47 etc., wherein the normal position of the two movable blades of a pair results in an open circuit, but the reversal of one of the movable blades of each pair gives a closed circuit through the two switches. The movable blades of switches 46 to 50 are connected to the ungrounded side of battery 26 and the movable blades of switches 36 to 40 are connected, respectively, to the five-channel circuit lines designated 56 to 60. Thus, assuming that the movable blades of switches 36 to 40 remain in their normal upper positions, the moving down of the blade of one of switches 46 to 50 connects the battery to the corresponding line 56 to 60. Similarly, assuming that the movable blades of switches 46 to 50 remain in their normal upper positions the moving down of the blade of one of switches 36 to 40 connects the battery to the corresponding line 56 to 60.

In this embodiment, the lower coils 51-2 to 55-2 are connected, respectively, to permutation switches 17 to 21 and the upper coils 51-1 to 55-1 are connected, respectively, to switches 41 to 45. Thus, coils 51-2 to 55-2 are energized in accordance with the code symbols of the various language characters written by the typewriter; whereas, coils 51-1 to 55-1 are energized in accordance with whichever of the particular switches 41 to 45 are closed at the time impulse switch 30 is closed. Switches 41 to 45 are closed in accordance with the cipher key, in the manner outlined above, by cipher discs 61 to 65 which are described more fully below. Cipher discs 61 to 65 are provided with projecting means so that as the discs are rotated in step-by-step fashion, they engage and close their respective switches in accordance with the cipher key.

As indicated above, the closing of impulse switch 30 transmits through the permutation unit the code signals which correspond to the character which is then being written by the typewriter. Furthermore, the closing of the various permutation switches results in the corresponding coils 51-2 to 55-2 being energized with the result that the armatures, or movable blades, of the appropriate switches 46 to 50 are moved down closing the lower switches and connecting the battery to the appropriate lines 56 to 60. However, this is upon the assumption that the upper coils 51-1 to 55-1 are deenergized,

and the energization of any one of these upper coils causes a reversal of the corresponding switch 46 to 50. Thus, the sign of the code element passing over a particular line 56 to 60 is reversed by the energization of the appropriate coil 51-1 to 55-1. In this way if the code element on a particular line from the permutation unit is "on" or "plus," the energization of the corresponding upper coil 51-1 to 55-1 reverses the sign of that code element to an "off" or "minus"; and similarly, an "off" or "minus" element is changed to an "on" or "plus" code element. Assume, for example, that switch 41 is closed and switches 42 to 45 remain open; then the closing of impulse switch 30 transmits a signal impulse through such of permutation switches 17 to 21 as are then closed and simultaneously sends a signal impulse through switch 41 to energize coil 51-1. This reverses every code element which passes over the "#1" line 56 so that the code alphabet of the above "Table No. 1" is changed to the scrambled alphabet of "Table No. 2."

A further reversal of the individual code elements is performed by switches 36 to 40 there being cipher discs 66 to 70 which move the respective switch blades from their normal upper positions to their lower positions in accordance with a predetermined cipher key. Thus, a preliminary enciphering effect is imposed onto the coded message by switches 41 to 45 and a second enciphering effect is imposed by switches 36 to 40. Switches 41 to 45 are connected to switch 30 through a manual switch 71 which may be opened to stop the enciphering operation by 35 these switches. Discs 66 to 70 may be stopped in a position where all of the movable switch blades are in the upper position so that this cipher effect is not imposed. In this way, the code symbols from the permutation unit are transmitted unciphered over lines 56 to 60.

As indicated above, the code characters of a message are separated into five-character groups by inserting a space after each fifth code character. The telegraphic code signal for a space is, according to the conventional five-unit code, an impulse over line #3 only, and therefore, means is provided to transmit an impulse over this line (line 58) after each fifth code character. This operation is performed by a circuit shown at the right-hand side of the wiring diagram, there being a switch 72 which is associated with cipher switches 41 to 45 and which is connected at one side through a manual switch 73 to battery 26 and at the other side through a self-opening relay 74 to line 58. Switch 72 is provided with a disc 75 which closes switch 72 when the character after each fifth character is to be transmitted. Thus, switch 72 is closed as the permutation switches 17 to 21 and the cipher switches 41 to 45 are being arranged for the transmitting of the sixth code symbol and each fifth code symbol thereafter; i.e., the eleventh, sixteenth, etc. The closing of switch 72 causes an initial impulse to pass through the switch of relay 74 to line 58, and simultaneously, the coil of relay 74 is energized so that the switch of the relay is immediately opened. In this way, a space signal is transmitted over the line prior to the transmitting of the character signal, and the opening of the switch relay 74 prevents interference with the code signal which is transmitted by the closing of impulse switch 30.

In a system of this type, it is desirable to provide an automatic check-signal device in order

to insure that each code signal is transmitted to the receiving station. Accordingly, as shown at the left of the figure, means is provided to give such an automatic check. Thus, a rockable ratchet member 76 is frictionally held in the central position shown, but it is adapted to rock clockwise to close a switch 77 or to rock counterclockwise to close a switch 78. On the right-hand side of the ratchet member is a set of ratchet teeth which are engageable by a dog on the end of a swingable armature 79, and similarly, on the left-hand side of the ratchet member is a set of oppositely disposed ratchet teeth which are adapted to be engaged by a dog on a swingable armature 80. Armature 79 is urged to the upper position as shown by a spring 81, and it is swung downwardly by the energization of a solenoid 82 which has one side grounded and the other side connected to a normally open switch unit of switch 23 so that solenoid 82 is energized each time that the impulsing solenoid 25 is de-energized. Armature 80 is urged to its upper position by a spring 83 and it is swung downwardly by the energization of the solenoid 84. Solenoid 84 has one side grounded and has its other side connected through a line 85 to a monitoring unit of the system (such as typewriter #2 in Figure 1), and the arrangement is such that a signal impulse is transmitted over line 85 to energize solenoid 84 each time that a character symbol is received at the monitoring unit.

Each time that armature 79 swings down, its dog engages a tooth on the ratchet member, and when the solenoid 82 is deenergized, spring 81 pulls the armature up and swings the ratchet member counterclockwise the distance of one tooth. Due to the friction mounting of the ratchet member, the ratchet member remains in each new position until moved further. In a similar manner each time that the armature 80 swings downwardly, its dog engages a tooth on the ratchet member, and when the solenoid 84 is deenergized, spring 83 pulls the armature back up and swings the ratchet member clockwise the distance of one tooth. Thus, the alternate energization of solenoids 82 and 84 produces oscillation of the ratchet member from and to the position shown. However, if a signal group is transmitted which is not received, solenoid 82 is energized more often than is solenoid 84 with the result that the ratchet member is stepped counterclockwise sufficiently to close switch 78. Switch 78 is connected to a bell 86 the other side of which is grounded and when switch 78 is closed the bell is energized and this notifies the operator of the faulty operation. Similarly, switch 77 is connected to a bell 87, the other side of which is grounded, and if a fault occurs in the system so as to cause an extra signal to appear in the receiving station, solenoid 84 is energized more often than is solenoid 82; and, this causes the ratchet member to swing clockwise sufficiently to close switch 77 so that bell 87 is energized and the operator is notified of this fault.

The construction and operation of switches 36 to 40, 41 to 45, and 72, and the cipher discs which operate these switches will now be discussed with specific reference to Figures 3 to 7. Referring particularly to Figure 3, switches 36 to 40 are shown at the right of the figure in a vertical bank designated at 90 mounted on a bracket 91 together with their cipher discs 66 to 70. These discs are designated at 92 and are mounted together so as to form a cipher disc assembly which is manually rotatable as a unit about a fixed

vertical shaft 93. At the center of the figure switches 41 to 45 and 72 are shown in a similar vertical bank, designated 94 mounted on a bracket 95, and the cipher disc assembly, formed by operating discs 61 to 65 and 75, is designated at 96 and is rotatably mounted on a vertical shaft 97.

Switches 41 to 45 and 72 are operated individually by their cipher discs through levers 98 pivoted at 99 on bracket 95 with each lever having at its left-hand end a fiber disc 100 which engages the movable blade of its switch. When the lever is rocked between the normal position and the position shown, the movable blade is moved to close the switch. Levers 98 are rocked by engagement with removable U-shaped clips 101 carried by the cipher discs, the construction of which is shown best in Figures 5 and 7. Each disc has sixty peripheral slots 102 (Figure 7) each of which is adapted to carry a removable U-shaped clip 101 (Figure 5). Eight discs are mounted together on a hexagonal mandrel 103, these being the cipher discs 61 to 65, spacing disc 75 and two additional discs 104 and 105. Mandrel 103 also carries at its lower end a ratchet wheel 106. The discs are clamped on the mandrel by a knurled nut 107 and the hexagonal shape of mandrel 93 holds the discs from turning on the mandrel.

Reverting to Figure 3, the cipher disc assembly 96 is rotated step-by-step on its fixed vertical shaft 97 by a solenoid-operating unit 108. This solenoid-operating unit includes a U-shaped magnetic core 108 which carries a solenoid 110 and which has a cylindrical air gap in which is rockably mounted an armature 111. Armature 111 is pivoted at 112 and is urged to the position shown by a tractive spring 113, fixed at one end to core 108 and having its other end extending around and attached to a sleeve 114 carried by the armature shaft. Thus, when solenoid 110 is energized, armature 111 is rocked counterclockwise against the tension of spring 113; then, when the solenoid is deenergized, spring 113 rocks the armature back to the position shown.

Pivoted to the lower end of armature 111 and in alignment with ratchet wheel 106 is a sliding dog 115, the nose end of which is adapted to engage the teeth of the ratchet wheel. The rocking of armature 111 which results from the intermittent energization of solenoid 110 causes dog 115 to slide longitudinally, and the movement is such that each time that the dog is retracted, the end of the dog picks off one tooth of the ratchet wheel. Thereafter, when solenoid 110 is deenergized the armature 111 is swung back to the position shown and rotates the cipher disc assembly the distance of one tooth. At the left-hand side of the nose of dog 115 is a fixed post 116 and as the dog slides to the position shown, its nose engages post 116 so as to hold the dog into engagement with the ratchet wheel (as shown). When the dog is thus positioned the ratchet wheel and therefore the entire cipher disc assembly is locked in position so that it cannot rotate. The relationship between the nose of dog 115 and the end of levers 98 is such that each time that the cipher disc assembly is stopped, there is a slot 102 directly at the ends of the levers. If the particular slot at the end of a lever carries a clip 101, the end of the clip engages the lever and swings the lever to the position of the top lever shown thereby swinging the switch blade to the switch-closing position.

Dog 115 carries a pin 116' which is positioned in the fork of a yoke 117 which is pivotally held

by a screw 118 and the opposite end of which is operatively engaged with the movable blade 119 of a two-position switch 120. When blade 119 is engaging contactor 121 (as shown), the circuit to solenoid 110 may be closed, but when the armature rocks into engagement with the other contactor 122, the circuit to this solenoid 110 is open, and further, a keyboard-locking mechanism is energized to lock the keyboard of the transmitting typewriter. Thus, each time the dog reaches its fully retracted position as it oscillates to rotate the cipher disc assembly, switch 120 effects the deenergization of solenoid 110 and also effects the locking of the typewriter keyboard.

With apparatus of this type it is desirable to provide for setting the cipher disc assembly 96 to a predetermined "home position" at the start of a message; and disc 105 (Figures 5 and 6) initiates the carrying out of this function automatically. The switch in bank 94 which is operated by disc 105 is connected in series with a manual "homing switch" (not shown) to provide a power circuit through switch 120 to solenoid 110. It will be noted that disc 105 carries a clip 101 in all of its slots 102 except the slot designated 102-1. Slot 102-1 is the slot which is at the lever 98 for this disc at the time the disc assembly is in the "home position." Thus, when the disc assembly is in any position other than the "home position," the switch associated with disc 105 is closed and the closing of the manual homing switch completes a circuit through switch 120 to solenoid 110 so as to energize the solenoid; the disc assembly is rotated step-by-step as long as the homing switch is held closed or until the disc assembly reaches the home position with slot 102-1 at the lever 98.

As pointed out above, the cipher key depends upon which of switches 41 to 45 are closed during the enciphering of the various characters. With this particular set of cipher discs 61 to 65, etc., there are sixty slots in each disc and the clips 101 are placed around each disc in a random manner. Thus, starting from the home position, the vertical rows of slots are passed serially step-by-step past the levers 98, and in each stationary position of the cipher discs one (or more) of the levers is rocked to impose the cipher effect in accordance with the cipher key. When it is desirable to change the cipher key, nut 107 is removed and the various discs are turned about the mandrel to new positions, and the nut is then replaced. For a further changing of the keys, the positions of the various clips 101 may be changed and clips may be added or taken away.

Cipher disc assembly 92 is similar to disc assembly 96 except that the discs 66 to 70 are smaller and have only thirty slots. The slots are here designated 123 and the clips which are the same as clips 101 are designated 124. The top of disc assembly 92 carries a plate 125 which is marked to indicate the position of the disc assembly, with relation to a pointer on the stationary shaft 93. At the base, the disc assembly has a ratchet wheel 126 by which the disc assembly is rotated. A spring-pressed detent 127 holds the disc assembly from clockwise movement and a spring-pressed dog 128 has its nose engaging the ratchet wheel and is pivoted at its opposite end on a lever 129 which is rockably held by a screw 130. Lever 129 extends from the front of the machine and is swung counterclockwise from the position shown to cause the nose of the dog 128 to gather a tooth of the ratchet wheel; lever 129 is then released,

and a spring 131 returns the elements to their positions shown, and in doing so, advances the disc assembly the angular distance of one tooth which is also the angular distance between adjacent slots 123. The switches of bank 90 are operated by levers 132 which are pivoted at 133 and operate in the same manner as do levers 98. The clips 124 on the discs of the disc assembly 92 are placed at random in accordance with the cipher key, and they impose their ciphering effect as outlined above. In practice the position of disc assembly 92 is changed manually in accordance with a predetermined key so that the ciphering effect imposed by these cipher discs is constant for some period. However, as outlined above, the ciphering effect of switches 41 to 45 and discs 61 to 65 is changed after each character has been transmitted so that it repeats its cipher after sixty characters have been enciphered. When desirable, the ciphering effect of disc assembly 92 and its switches may be changed after every sixty characters so that an endless chain cipher is obtained.

In accordance with one embodiment of the invention, the discs of the two cipher disc assemblies 92 and 96 are individually mounted and rotated step-by-step in accordance with a predetermined key. Thus, after each character has been enciphered, one or more of the various cipher discs is moved to the next position. In this way, the cipher key depends upon the position of the clips in the slots on the cipher discs and also upon the key by which the various discs are rotated. In Figure 8, an arrangement is represented schematically for advancing the cipher discs individually. By this arrangement, the advancing of the discs is under the control of a slowly rotating cam assembly, and the rotation is performed by a solenoid assembly. In Figure 8 only a single cipher disc is represented, it being understood that additional discs would involve a duplication of the structure shown. Accordingly, a disc 133 is mounted on a shaft 134, but a friction clutch (not shown) prevents free rotation of the disc. A ratchet wheel 135 fixed to the disc provides for a step-by-step rotation of the disc by a dog 136 engaging the ratchet wheel. Dog 136 is carried by a lever 137 which is pivoted at 138 and urged clockwise by a spring 139. A constantly rotating cam 140 is positioned so as to rock lever 137 counterclockwise against the action of spring 139. At the bottom of the lever a solenoid 141 may be energized to hold the lever against the action of the spring so that the upper end of the lever does not follow the same. Thus, by energizing solenoid 141, the lever remains stationary, but if the solenoid is deenergized during one revolution of cam 140, spring 139 causes the lever to follow the cam so that the dog is retracted and it gathers one tooth on ratchet wheel 135. Upon further rotation of the cam, the cam swings the lever back, and the cipher disc is rotated the distance of one tooth pitch.

When dog 136 is projected counterclockwise, its nose moves beneath a fixed pin 157 (shown in broken lines) so that the cipher disc is latched in position at the end of each step-by-step movement. Thus, a cipher-disc locking arrangement somewhat similar to that shown in Figures 1 to 7 is provided. In Figure 8 the clips are indicated at 158, the switch lever is indicated at 159, and the two-position switch is indicated at 160. However, the operation is the same as in the embodiment of Figures 1 to 7.

Solenoid 141 is energized by a battery 142.

through a switch 143, and the switch is normally open but is closed in accordance with the contour of a cam 144. The contour of cam 144 is such that it closes switch 143 and thereby energizes solenoid 141 in accordance with a predetermined key. Thus, at the beginning of a ciphering operation the cipher discs are in a predetermined home position and the cams, including cam 144, are started rotating and they step the cipher discs ahead on shaft 134 in accordance with the contour of the cams. The arrangement is such that one or more of the cipher discs is stepped ahead cyclically. Thus, the cipher effect is changed after the transmitting of one or more characters. The cipher key may be readily changed by merely changing the cams or by changing the cipher discs.

As indicated above, at the beginning of the ciphering operation, the cipher discs are in a predetermined home position. Accordingly, shaft 134 carries a homing disc 145 which has a tooth 146 which may be engaged by a homing lever 147. Homing lever 147 is spring-urged upwardly to the position shown by a spring 148 and is drawn down to engage tooth 146 by the energization of a solenoid 149. A similar homing lever 150 is mounted so as to engage a tooth 151 on disc 133. Lever 150 is spring-urged upwardly by a spring 152 and is drawn down by the energization of a solenoid 153. One side of solenoid 149 is grounded and the other side may be connected through a manual switch 154 to a battery 155 the other side of which is grounded. Similarly, one side of solenoid 153 is grounded, and the other side 35 may be connected through a switch 156 to battery 155. Each of the cipher discs has a similar homing lever and solenoid mechanism and all of the homing solenoids 153 are connected in parallel.

40 Prior to the beginning of a ciphering operation, switch 156 is closed manually, and cam 140 is positioned so that its flat is engaged by its lever 137; also, solenoid 141 is deenergized with the result that dog 136 is withdrawn from the ratchet wheel; the corresponding dogs on the other cipher discs are also withdrawn. Shaft 134 is then rotated through a slip clutch (not shown), and this rotation carries each of the cipher discs around until its tooth 151 engages its homing lever 150; the cipher discs then are held even though the shaft is rotated, and the cipher discs are positioned in a predetermined home position. Thereafter, with solenoids 153 still energized, switch 154 is closed so as to energize solenoid 149 and swing homing lever 147 to the position shown. On the next revolution of shaft 134, tooth 146 engages lever 147, and the rotation of the shaft is stopped. In this way the cipher discs are positioned in a predetermined position on shaft 134 and shaft 134 is held in a predetermined position. Therefore, all of the cipher discs can be rotated together to give them a predetermined starting position other than the normal home position.

As indicated above, Figure 1 represents an operating condition where the tape reader controls the other elements of the system so that typewriter #1 types a plain language message on a sheet 12, tape punch #1 produces a punched tape 14 which is identical with the tape 9 being read, typewriter #2 types the enciphered language message on a sheet 170, and tape punch #2 punches a tape 171 bearing the enciphered code message. For purposes of explanation, tape 9

bears in plain language the three words of the message which appears punched therein and this portion of the message is as follows:

YOUR LETTER OF

* * * * *
* * * * *
* * * * *
* * * * *
* * * * *

After enciphering, these three words of the message are written on sheet 170 by typewriter #2 and punched into tape 171 in tape punch #2 as follows:

* * * * *
* * * * *
* * * * *
* * * * *
* * * * *

HZQBD RPLKA RXQBM

It will be noted that the twelve letters forming the first three words of the message and the three spaces following these words are enciphered into fifteen characters, and these fifteen characters are separated into three groups of five characters each. Typewriter #2 monitors the message so that an error, such as an omission of a character, can be readily detected. Tape 171 may be read by another tape reader and transmitted over an outgoing signal channel as desired.

As many possible embodiments may be made of the mechanical features of the above invention and as the art herein described might be varied in various parts, all without departing from the scope of the invention, it is to be understood that all matter hereinabove set forth, or shown in the accompanying drawings is to be interpreted as illustrative and not in a limiting sense.

I claim:

1. In ciphering apparatus having means for producing successive character code signals representing a straight language message according to a predetermined combinational-position code system and a first group of contacts each selectively adjustable to an on and an off electrical condition in correspondence to said code signals and a group of differential code relays each having a first coil corresponding to contacts of said first group of contacts and a second coil corresponding to contacts of a second group of contacts, said first coils being responsive to the electrical condition of the corresponding contacts of said first group of contacts; a second group of contacts corresponding to contacts of said first group and each connected to a corresponding second coil of said code relays for rendering said coil responsive thereto when said second group of contacts are selectively adjusted to on and off electrical conditions to produce a signal for each of said character code signals; a series of cipher discs each corresponding to contacts of said second group of contacts and mounted in spaced relation on a rotatable shaft and in spaced relation to contacts of said second group; a ratchet wheel fixedly mounted on said shaft; actuating devices attachable to and detachable from the periphery of said discs to enable said disc upon rotation to selectively adjust the electrical condition of said second group of contacts in a pre-selected cyclic pattern and means for rotating said discs in step-by-step fashion, said means including a rotatable solenoid-operated armature resiliently urged against rotation, a dog pivotally

mounted on said armature from the center thereof and extending therefrom into urged engagement with the periphery of said ratchet wheel so that energization of the solenoid causes said armature to rotate in one direction and said dog to engage the next tooth of the ratchet wheel and deenergization thereof causes the armature to be rotated in the other direction and rotate said shaft an amount corresponding to the displacement of one tooth of the ratchet wheel.

2. In ciphering apparatus five pairs of contacts and a pair of grouping contacts each having on and off electrical conditions representing positive and negative manifestations; five cipher discs, a ratchet wheel and a grouping disc mounted in spaced relation on a common shaft, each cipher disc corresponding to one of said contact pairs and said grouping disc corresponding to said grouping contacts; actuating devices attachable to and detachable from the peripheries of said discs for changing the electrical condition thereof at preselected times during the rotation of said discs; means for rotating said discs in step-by-step fashion, said means including a rotatable solenoid-operated armature spring urged against rotation, a dog pivotally mounted on said armature from the center thereof and extending therefrom into urged engagement with the periphery of said ratchet wheel so that energization of the solenoid causes said armature to rotate in one direction and said dog to engage the next tooth of the ratchet wheel and deenergization thereof causes the armature to be rotated in the other direction and rotate said shaft an amount corresponding to a displacement of one tooth of the ratchet wheel; a series of pivotally mounted arms each corresponding to one of said discs and one of said pairs of contacts and having one end urged toward its corresponding disc and operative at its other end to change the electrical condition of the corresponding contact pair when rotated from the disc, said actuating devices contacting the corresponding pivoted arms to effect rotation of that arm from the disc immediately after preselected step-by-step operations of the ratchet wheel; said actuating devices being arranged on the periphery of said grouping disc to close said grouping contacts upon each fifth manifestation; a relay in series with said grouping contacts and energized upon the closing thereof to open the circuit to its armature.

3. In ciphering apparatus having a first line carrying signals corresponding to the enciphered signals produced and a second line carrying signals corresponding to the enciphered signals received by a monitoring unit; a rotatable ratchet wheel carrying an arm extending therefrom and having a first and a second series of teeth, each on opposite portions of the periphery thereof, one of said series being arranged to effect rotation in one direction and the other in the opposite direction; a first and a second solenoid energizable from said first and second lines respectively; a first and a second armature actuated respectively by said solenoids; a first dog mounted on the first armature and engageable with the teeth of one of said series when said first solenoid is energized and a second dog mounted on the second armature and engageable with the teeth of the other of said series when said second solenoid is energized; a pair of contacts having off and on electrical conditions controlled by said arm and mounted on either side of said arm in spaced relation thereto; an indicating device connected to each pair of contacts and operable in accordance

with the electrical condition of said contacts; spring members attached to each of said armatures and operable when the respective solenoids are deenergized to rotate said ratchet wheel to displace said arm a predetermined distance, alternate deenergization of said first and second solenoids causing equal and opposite displacement of said arm and consecutive deenergization of either solenoid causing a closing of the corresponding pair of contacts by said arm to operate 10 the indicating device connected thereto.
